UNITED STATES PATENT OFFICE.

LEVI K. FULLER, OF BRATTLEBOROUGH, VERMONT, ASSIGNOR TO J. ESTEY & CO., OF SAME PLACE.

IMPROVEMENT IN TREMOLOS FOR REED ORGANS.

Specification forming part of Letters Patent No. 121,609, dated December 5, 1871.

To all whom it may concern:

Be it known that I, LEVI K. FULLER, of Brattleborough, in the county of Windham and State of Vermont, have invented an Improvement in the Tremolo of Reed Organs, of which the following is a specification:

My invention consists in an improved stop-mechanism, whereby the motion of the fan can be instantly arrested by the interposition of a resisting medium to overcome the rotation.

Figure 1 is a perspective of my improvement showing the device for arresting the motion of the tremolo. Fig. 2 is a sectional view of Fig. 1, with the box containing the driving-wheel and stop-mechanism in elevation, and showing the operation of the same by means of dotted lines.

As represented in the drawing, A is the action-board, and B the box containing the motor-wheel, which is revolved by a current of air from the bellows, rotating the shaft D, and causing a corresponding movement of the fans e e, by which the tremulous effect is produced. E is a sliding-bar, which is supported on the box by brackets a a or other equivalent means. J is a lever having one end pivoted to the box B, and the other connected by the link h to the sliding-bar E. This lever is provided with a projection, i, which is brought into proximity and removed from the

pin b on the fan-shaft by the action of the lever J. When the sliding bar is drawn the link h assumes a position which depresses the lever J sufficiently to remove the projection i from contact with the pin b, leaving the shaft free to revolve. In order to arrest the motion of the tremolo, the slide is pushed back, as shown in Fig. 2, when the lever J is brought into such position that the projection i meets the pin b and stops the rotation of the shaft D. K is a rod which connects the lever J with a valve underneath the action-board, which is opened by the downward thrust of the lever simultaneously with the release of the pin b, admitting a current of air to act upon the wind-wheel and rotate the fan-shaft D.

I claim as my invention—

The combination of the stop-lever J, connecting-rod h, and slide E with the spur b, or its equivalent, for controlling the motion of the fan-shaft D in parlor organs, substantially as set forth.

In witness whereof I have hereunto signed my name in the presence of two subscribing witnesses.

LEVI K. FULLER.
